WOMAN'S STOCKING OR SIMILAR ARTICLE

Otto W. Grummt, Philadelphia, Pa.

Application June 22, 1949, Serial No. 3,456

Term of patent 14 years

(Cl. D47—7)

To all whom it may concern:

Be it known that I, Otto W. Grummt, a citizen of the United States, residing at Philadelphia, in the county of Philadelphia and State of Pennsylvania, have invented a new, original, and ornamental Design for a Woman's Stocking or Similar Article, of which the following is a specification, reference being had to the accompanying drawing, forming part thereof, in which:

The figure is a side elevation of a woman's stocking embodying my design.

I claim:

The ornamental design for a woman's stocking or similar article, as shown.

OTTO W. GRUMMT.
